UNITED STATES PATENT OFFICE.

DAVID H. DAVENPORT, OF VANCOUVER, WASHINGTON.

BED-RAIL JOINT.

Application filed June 5, 1922. Serial No. 565,790.

To all whom it may concern:

Be it known that I, DAVID H. DAVENPORT, a citizen of the United States, residing at Vancouver, in the county of Clarke, State 5 of Washington, have invented a new and useful Bed-Rail Joint; and I do hereby declare the following to be a full, clear, and exact description of the invention, such as will enable others skilled in the art to which 10 it appertains to make and use the same.

The invention relates to bed rail joints and has for its object to provide a device of this character wherein the bed rail is provided with a recess in its end for the reception 15 of an elongated member carried by the bed post and held in the bed post by means of a transversely disposed pin, the ends of which extend beyond the opposite sides of the bed post and receive the hooked ends of 20 hooks pivoted to the opposite sides of the rail, the hooks forming means for rigidly holding the rail and bed post together.

With the above and other objects in view the invention resides in the combination and 25 arrangement of parts as hereinafter set forth, shown in the drawings, described and claimed, it being understood that changes in the precise embodiment of the invention may be made within the scope of 30 what is claimed without departing from the spirit of the invention.

In the drawings:—

Figure 1 is a side elevation of a conventional form of bed showing the rail holding device applied thereto.

Figure 2 is a top plan view of a bed rail and the adjacent bed posts showing the rail holding device.

Figure 3 is an enlarged side elevation of one end of said rail and a portion of the bed post, parts being broken away and showing the rail holding device.

Referring to the drawings, the numeral 1 designates a rail of a conventional form of 45 bed, and 2 bed posts to which the rail is secured. The ends of the rail 1 are provided with recesses 3 for the reception of the rectangular shaped members 4, which members extend through registering apertures 5 in the posts 2 and are preferably provided with heads 6 which engage the outer faces

7 of the posts 2 and brace the same. The members 4 are held in the apertures 5 by means of transversely disposed pins 8 which extend through the posts 2 and members 4 55 and have their ends 9 terminating beyond the opposite faces of the posts 2. Pivots connected to the rail 1 adjacent its ends at 10 are bars 11, the free ends of which bars are provided with notches 12 which receive 60 the ends 9 of the pins 8 and hold the ends of the rail 1 in close abutting engagement with the inner sides of the posts 2 thereby thoroughly bracing parts and at the same time forming a rail joint for a bed, which 65 may be easily and quickly disconnected and one wherein jamming tapered surfaces are eliminated thereby obviating the jamming of parts which is now the common difficulty in beds.

When it is desired to disconnect the rail, the operator pulls upwardly on the levers 11 until the ends 9 of the pins 8 are out of the notches 12, at which time the bed posts and rail may be easily separated.

From the above it will be seen that a bed rail joint is provided, which is simple in construction and one wherein the parts have been reduced to a minimum thereby allowing 70 a positive action of the parts.

The invention having been set forth what is claimed as new and useful is:—

The combination with a bed rail and a bed post, of a connection between said post and rail, said connection comprising a member 85 extending through the post and into a recess in the end of the rail, a pin extending transversely through the post and said member the ends of said pin extending beyond the outer opposite faces of the posts 90 and bars pivoted to the opposite faces of the rail at a point spaced from its end and having notches for the reception of the ends of the pin.

In testimony whereof I have signed my 95 name to this specification in the presence of two subscribing witnesses.

DAVID H. DAVENPORT.
